GAS BURNER

Filed Aug. 24, 1931

UNITED STATES PATENT OFFICE

ALBERT W. MORSE, OF FOREST HILLS, NEW YORK

GAS BURNER

Application filed August 24, 1931. Serial No. 558,909.

This invention relates to gas burners or similar structures in which atmospheric air is inspirated into the gas by the relatively high velocity of the gas itself. Burners of this kind are especially applicable to steam boilers or other furnaces with a natural draft. It is the particular object to provide such a burner with means to regulate the amount of atmospheric air drawn into it by the velocity of the gas jet in certain predetermined proportions to each other during a unit movement of an operating lever or the like. Another object is to provide an additional inlet for atmospheric air between the burner and the furnace forming a structural part of a burner support, through which secondary air is drawn by the natural draft of the furnace or boiler assisted by the velocity of the aforesaid combined gas and primary air mixture, and to interlock the gas, primary and secondary air. That is, the invention resides in means whereby a fixed proportion between a primary and secondary air and the gas supply can be established and an operating screw or lever can be moved a fixed distance while the gas and primary and secondary air can be adjusted to desired proportions independent of the fixed travel of the said lever or screw.

This application is in fact an adaptation of the principles of construction and operation brought out in my copending applications filed, respectively, April 28, 1931, Serial #533,407 and July 9, 1931, Serial #549,656.

Other objects will become apparent in the accompanying drawing and the following specification in which a preferred form of the invention is described.

In the drawing, Fig. 1 is a vertical longitudinal sectional view through a gas burner embodying the principles of the invention;

Fig. 2 is a cross sectional view along the plane of line 2-2 in Fig. 1;

Fig. 3 is a fragmentary horizontal sectional view along the plane of line 3-3 in Fig. 2;

Fig. 4 is a fragmentary elevational view of part of the operating mechanisms of the burner;

Fig. 5 is a fragmentary cross sectional view through the air register at the outlet end of the burner from which a furnace plate and combustion block have been omitted; and

Fig. 6 is a fragmentary elevational view 55 of the gas burner.

Like characters of reference denote similar parts throughout the several views and the following specification.

10 is a substantially tubular burner casing or inspirator, having an enlarged bowl shaped inlet 11 and an exteriorly threaded portion 12 adjacent thereto. Supported in the center of the inlet bowl 11 by means of ribs 13 and a tubular bracket 14 is a bushing or gas nozzle holder 15. The annular space around bracket 14 and the inside of bowl 11 forms an inlet 16 for primary atmospheric air into the inner or mixing portion 17 of the inspirator 10. Screwed into the outlet end of the gas nozzle holder 15 is a gas nozzle 18 having a small outlet 19 and an enlarged inlet end 20 converging toward the outlet 19. The inlet end of the holder 15 is tapped to receive one end of a gas tube 21. The central portion of the holder 15 is provided with a central support 22 for a gas regulating spindle 23. 24 are a number of ports through the support 22 around the spindle 23 and connecting the inlet and outlet of the nozzle holder 15. The other end of the gas tube 21 is threaded to receive a T 25, having an inlet 26 at its bottom. 27 is a stuffing box gland in the T, opposite its connection to the gas tube, the gas regulating spindle 23 projecting through the T and gland 27 outwardly thereof and being threaded at 28 and provided with preferably a screw driver slot 29 at its end. 30 is a primary air shutter of substantially conical shape, its large annular base adapted to contact with the end faces of the inlet bowl 11 of the inspirator and its apex being tapped to receive one end of a tubular guide 31 which is concentric with and preferably slidably engages the outside of the gas tube 21. The other end of the guide is threaded at its outside at 32.

Fastened to a projecting lug 33 of the inlet bowl 11 of the inspirator by means of suit-

able bolts 34 is a bracket 35. This bracket is bent upwardly at its extreme end at 36 in tubular shape to receive a fulcrum pin 37.

38 is a substantially U-shaped lever straddling both sides of end 36 of the bracket 35 and is fulcrumed on pin 37. 39 is a handle piece fastened to lever 38. Lever 38 has at each side outwardly extending lugs 40 and 41 spaced, respectively, above and below the 10 fulcrum pin 37. These pairs of lugs are bored out to receive each a screw 42 disposed parallel to the lever 38, having a head 43 below the lower lug 41 and a square 44 for manipulating with a wrench at its top and a lock nut 15 45 above the upper lug 40 to hold the screw in a fixed position.

46 is a substantially square block in threaded engagement with one of the screws 42 and disposed between the lugs 40 and 41, its wide 20 surface adjacent the lever preventing a turning movement when screw 42 is rotated about its axis which thus forces the block up and down when the screw is turned. 47 is a pin 25 projecting outwardly from the block away from the lever. 48 is a lever link connecting the pin 47 with a similar pin 48a forming part of a link 48b which is screwed over the threaded end 28 of the gas regulating spindle 23.

30 49 is a square block similar to block 46 and similarly disposed upon screw 42 at the other side of the lever 38, having also a pin 50 projecting therefrom. 51 is a threaded sleeve 35 screwed onto the externally threaded end 32 of the guide 31. Sleeve 51 is provided with a pin 52. A lever link 53 connects pins 50 and 52.

The inspirator tube 10 is screwed into a support 54 which consists of a circular flange 49 55 fastened to a furnace plate 56 by means of screws and nuts 57. 58 is a central aperture through flange 55 in alignment with the inspirator 10 and a combustion block 59 immediately adjacent to it. 60 are lugs carrying a cup-shaped collar 61 into the center of which is screwed the inspirator 10 for the purpose of adjustably supporting the same and thereby the whole burner structure. The space between flange 55 and the collar 61, 59 defined by the length of lugs 60, forms a passage around the inspirator 10 for secondary air to enter the boiler or furnace through aperture 58. 62 is a cylindrical shell 55 slidably engaging the outside of collar 61 and lugs 60 forming an air register therewith and being adapted to close entirely the space between collar 61 and flange 55. At each side shell 62 has a U-shaped groove 63 within which is slidably disposed a head 64 of a screw 65, the stem of which travels within an elongated slot 66 in the shell 62.

67 is a yoke comprising arms 68 and a center collar 69 which is slipped over lever handle 39 and adjustably secured thereto by 65 means of a set screw 70. 68a are lugs pro-

jecting from the arms 68 for the purpose of supporting the same against lever 38. To the lower ends of the arms 68 is secured by means of the usual bolt and nut 71 a connecting bar 72 at each side of the burner. 70 The other end of each connecting bar is fastened by a nut 73 to screw 65 at each side of shell 62, the elongated slot 66 permitting the shell to be fastened to the connecting bar in a more or less open or closed position 75 relative to the secondary air passage.

The operation of the burner is as follows: Gas, under relatively high pressure, is admitted through inlet 26, T 25, gas tube 21, ports 24, past the conically shaped end of the gas spindle 23, through gas outlet 19 into the inspirator 10, there, by reason of its velocity, to draw in atmospheric primary air through inlet 16, which mixes with the gas within the inspirator 10 and is discharged 80 therefrom at its outlet end passing into the furnace through aperture 58.

By screwing down the block 46 from a position just below the upper lug 40 to a position in line with the fulcrum pin 37, the opening between the conical end of the gas spindle 23 and its seat which is adjacent the gas outlet 19 of the nozzle 18 can be adjusted to regulate the amount of gas passed therethrough from a maximum to minimum 85 or zero. It can readily be noted that with the block 46 in its top position, when the lever 38 is moved from a closed to an open position, the link 48 and consequently the gas spindle 23 has its longest travel, while 90 when the block 46 is screwed down to be in alignment with fulcrum pin 37 there will be no movement at all of the link 48 and therefore no movement of the spindle 23.

Similarly, when the block 49 is in its top 105 position, the lever link 53, the threaded sleeve 51, the guide 31 and the primary air shutter 30 have the longest travel, resulting in the largest air opening, while with the block 49 screwed down to align with pin 37 110 there will be no movement of the shutter 30 at all.

In the same manner, the travel of the shell 62 or, in other words, the opening or closing of the air register for the control of secondary air into the boiler or furnace, can be controlled by adjusting collar 69 of the yoke 67 so that bolts and nuts 71 are brought in alignment with the fulcrum pin 37 in 115 which case there will be no movement at all of the shell 62, or the bolts and nuts are raised above the fulcrum sufficiently high to insure the maximum travel of the shell thereby opening or closing the air register 120 completely, adjustment of the air register 125 lying between these two points.

It is obvious, therefore, that with a unit movement of the lever 38, that is at a fixed full stroke, various adjustments of gas and primary air can be had by screwing down 130

more or less blocks 46 or 49 towards the center of the fulcrum pin 37, and that by raising or lowering yoke 67 the amount of secondary air may be controlled. This makes 5 possible the cross connecting of a battery of burners by connecting all levers of the burners to a motor driven automatic control or for other purposes. This can easily be effected because each burner or each set of 10 burners can still be adjusted to minimum as well as maximum flame conditions, but with a maximum (constant) stroke of the lever.

Attention is also drawn to the independently adjustable gas regulating spindle 23. This is a vital construction detail because it permits small variations in the assembly of the complete unit, by simply inserting a screw driver into the slot 29 and turning the 20 spindle until the gas opening around its conical inner end adjacent the gas outlet 19 has been properly adjusted.

Moreover, while the construction shown is particularly applicable to boilers or furnaces with stack draft, it may also be used in combination with similar devices where no stack draft is available. In such case the jet velocity of the flame induces through the register an amount of air which depends 30 upon the combined velocity of the primary air and gas.

Various changes in form, proportions and minor details of construction may be resorted to without departing from the principle 35 or sacrificing any of the advantages of the invention as defined in the appended claims.

What I claim as new, is:

1. A gas burner comprising an inspirator tube having a gas connection, an air shutter 40 at the inlet end of said tube, a gas valve, operating means for the said shutter and valve, and means to obtain variable ranges of adjustment for the said shutter and valve in predetermined proportions to each other from 45 zero to maximum with a constant travel of the said operating means.

2. A gas burner comprising an inspirator tube having a gas connection, an air shutter 50 at the inlet end of said tube, a gas valve, operating means for the said shutter and valve, and means to obtain variable ranges of adjustment for the said shutter and valve independently of and in predetermined proportions to each other from zero to maximum 55 during a unit travel of the said operating means.

3. A gas burner comprising an inspirator tube having a gas connection, an air shutter 60 at the inlet end and an air register intermed-

iate the inlet and the outlet of the said tube, a gas valve, operating means for the said shutter, valve and register, and means to obtain variable ranges of adjustment for the said shutter, valve and register in predetermined proportions to each other from zero to 70 maximum with a constant travel of the said operating means.

4. A gas burner comprising an inspirator tube having a gas connection, an air shutter 75 at the inlet end and an air register intermediate the inlet and the outlet of the said tube, a gas valve, a lever fulcrumed to the said tube adapted to operate the said shutter, valve and register, and adjusting means for varying the travels of the said shutter, valve and register independently of and in predetermined proportions to each other from zero to maximum during a unit movement of the said lever.

5. A gas burner comprising an inspirator tube, a gas nozzle at its inlet, a gas regulating spindle, a gas tube around the said spindle, having a gas connection, the said spindle projecting outwardly of the said tube, a tubular 90 guide slidably disposed around the said gas tube, an air shutter attached to the said guide and adapted to control the inlet of air to the said inspirator tube, a lever fulcrumed to the said inspirator tube, and means adjustably connecting the said spindle and guide to the said lever independently of each other for varying the travels of the said shutter and spindle in predetermined proportions to each other from zero to maximum during a constant travel of the said lever.

6. A gas burner comprising an inspirator tube, a gas nozzle at its inlet, a gas regulating spindle, a gas tube around the said spindle having a gas connection, the said spindle projecting outwardly of the said tube, a tubular 105 guide slidably disposed around the said gas tube, an air shutter attached to the said guide and adapted to control the inlet of primary air to the said inspirator tube, a register for the control of secondary air around the said inspirator tube intermediate its inlet and outlet, a lever fulcrumed to the said inspirator tube, and means adjustably connecting the said spindle, guide and register to the said lever independently of each other for varying the movements of said spindle, guide and register in predetermined proportions to each other from zero to maximum with a fixed 110 movement of the said lever.

In testimony whereof I have hereunto set my hand.

ALBERT W. MORSE.
